WASHING MACHINE PROVIDED WITH
REMOVABLE TRANSMISSION

Charles C. Scheele, Syracuse, N. Y., assignor to
Easy Washing Machine Corporation, Syracuse,
N. Y., a corporation of Delaware

Application December 18, 1947, Serial No. 792,363

14 Claims. (Cl. 68—26)

1

This invention relates to washing machines, and more particularly to a washing machine of the two-tub agitator and extractor type having a common transmission drive therefor.

In washing machines of the type indicated, the agitator and extractor drives are derived from vertical spindles extending through central apertures in the respective agitator and extractor tubs. In order to prevent the entry of water into the transmission, it has been the practice to provide shaft-protecting sleeves extending upwardly into the tub a substantial distance, and in the case of the agitator tub, usually above the normal water line. Such protecting sleeves have been generally provided at their upper ends with closely fitting shaft bearings, together with a suitable sealing arrangement, and have in general formed a part of detachable mechanism employed for securing the tub to the transmission from which the shafts extend. Excessive tolerances, variations in metal thickness, and other factors have caused disalignment of the sleeve contained shaft bearings due to the dual function, resulting in difficulty in maintaining seals and undue wear. In addition, the transmission and the shaft sleeves were secured to the tubs without consideration of the utilization of the transmission casing as a part of the frame of the washing machine proper for the purpose of rigidifying and strengthening the entire assemblage.

The present invention seeks to improve the over-all structural strength of a completely assembled washing machine by utilizing a transmission, in which the transmission housing is made a part of the frame structure of the washing machine. Additionally, the transmission is so constructed as to be rigid to the end that bearings are maintained in proper alignment regardless of tolerances in the assembly of the transmission to the washing machine proper and the incorporation of the transmission housing in the washing machine as a part of the frame structure thereof. The invention further has to do with the arrangement of moving parts within the transmission in such a manner as to assure against disalignment of the parts by the elimination of couples tending to disalign the moving parts, and in general to provide a transmission having characteristics of long life and minimum wear.

The above and other novel features of the invention will appear more fully hereinafter from the following detailed description when taken in conjunction with the accompanying drawings. It is expressly understood, however, that the draw-

2

ings are employed for purposes of illustration only, and are not designed as a definition of the limits of the invention, reference being had for this purpose to the appended claims.

5 In the drawings, wherein like reference characters indicate like parts:

Figure 1 is a perspective view of a two-tub washing machine, parts broken away, to which the invention is applied;

10 Figure 2 is a perspective view of a transmission assembly adapted for driving the elements shown in Figure 1;

Figure 3 is a section taken through the transmission of Figure 2 on a horizontal plane passing substantially through the center;

15 Figure 4 is a section taken substantially on the line 4—4 of Figure 3;

Figure 5 is a section taken substantially on the line 5—5 of Figure 3;

20 Figure 6 is a vertical section taken substantially on the line 6—6 of Figure 2;

Figure 7 is a section taken substantially on the line 7—7 of Figure 6; and

25 Figure 8 is a top plan view of the frame assembly.

Referring to the drawings and particularly to Figures 1, 2, and 4, there is shown a washing machine having a substantially cylindrical washing tub 10 having an oscillating vane type agitator 12 therein and a substantially cylindrical extracting tub 14 containing a centrifuge basket or extractor 16. The tubs 10 and 14 are secured to a skirt 18 constituting in part a frame structure, and a control panel 20 is arranged in the space between the tubs 10 and 14. The assembly is supported upon three or more legs 22. Located beneath the tubs and hidden from view by the skirt 18 is a unitary transmission structure shown in Figure 2. The transmission moving parts are contained within the transmission housing structure, which comprises a one-piece housing 24 having formed integrally therewith mounting lugs 26 and 28 at either end by means of which the housing may be secured to suitable angle members 30 and 32 secured to the skirt 18 and legs 22 by bolts 29 (see Figures 4 and 8). The skirt is formed from circular members 31 and 33 joined by connecting segments 35. The circular members are each offset as at 37 and 39 to telescopically receive the lower portion of the respective tubs and intervening U section resilient gasket material 41 arranged on the offsets 37 and 39.

40 The housing 24 is provided on its top side with a plurality of substantially circular openings 34, 36 and 38, two of which, 34 and 38, are provided

with cover plates 40 and 42 containing upstanding sleeve-like bearing-containing extensions 44 and 46 through which extend driving shafts 48 and 50 for the agitator 12 and the extractor 16, respectively. The sleeve members 44 and 46 project upwardly from somewhat elevated shoulders 52 and 54, adjacent to which are screw threads 56 and 58 which are adapted to project through suitable apertures provided in the bottom walls of the tubs 10 and 14. By means of 10 grommet-like sealing members 60 and 62 formed of rubber-like material, having a U-section and arranged about the apertures of the tubs 10 and 14, and suitable clamp nuts 64 and 66 threaded upon the threads 56 and 58, the tubs 10 and 14, 15 are securely fastened to the transmission in leak-tight fashion. It will be seen from the structure thus far described, that the tubs, the skirt and the transmission housing together form an integral unit the parts of which cooperate 20 with one another in providing strength and ruggedness.

The housing 24 is provided with a motor bracket 68 arranged in the form of a U, the arms of which have a semi-circular recess 70 into which the bearing journal ends of the motor 72 may be detachably secured by strap clamps 74 hooked upon the bracket ends as at 76 and tensioned by clamp screws 78 threaded in bracket held nuts 80, the screws and nuts lying in slots of cruciform shape. Such bracket is disclosed and claimed in Patent No. 2,598,836, issued June 3, 1952. The axis of the motor 72 is held by such bracket in substantial alignment with a worm shaft 82 extending substantially horizontally and diagonally through the housing 24 as will appear in Figure 3. The worm shaft 82 is supported upon spaced bearings, the bearing sleeves 84 and 86 of which are secured in cylindrical bearing apertures 88 and 90 integrally formed in the housing 24. The bearing sleeve 86 is adapted to absorb the thrust of the worms 92 and helical pinion or worm 94 positioned and secured upon the shaft 82, the sleeve 86 being positioned within the bearing aperture 90 by means of a set screw 96 (see Figure 2). A suitable packing 98 is provided around the shaft 82 and adjacent the bearing sleeve 86 in order to prevent leakage of lubricant contained within the housing 24. End play of the shaft 82 is prevented by a preloading arrangement urging the shaft 82 and the thrust collar 100 into engagement with the bearing sleeve 86 under a predetermined pressure. The means for providing such preloading of the shaft 82 is constituted by a spring 102 acting against a thrust ball 104 all of which are contained within an aligned cylindrical bore 106 in a suitable boss integral with the housing 24.

The worm 92 is adapted to drive the agitator 12, and oscillating motion is imparted thereto through an eccentric and sector gear arrangement having certain novel features which will appear from a careful consideration of the constructional details to follow. The worm 92 drives a worm wheel 108 which has integrally formed therewith on its under side an eccentric 110. The worm wheel is mounted upon a short stub shaft 112, the lower end of which is journaled in a bearing recess boss 114 integrally formed upon the housing 24. The upper end of the shaft 112 is journaled in a journal boss 116 formed as a part of a substantially circular cover plate 118 rigidly secured to the housing and accurately centered with respect to the housing by reason of the shoulder 120 and the housing aperture 122.

36. The cover plate is dished or conical, so that oil splashed upon the under side thereof runs to the center to lubricate the worm wheel bearing. The journal bosses 114 and 116 are such as to rigidly maintain the axis of the shaft 112 in accurate position with respect to the other parts and particularly the worm shaft 82.

Driven by the eccentric 110 is a connecting rod 122 having an internal ring 124 riding upon the eccentric 110, and a bifurcated end 126 containing a wrist pin 128. The wrist pin 128 is carried in a sector gear crank element 130 rocking on a shaft 132 secured in shaft receiving bosses 134 and 136, the former integrally formed in the housing 24 and the latter formed integrally with the cover plate 40. The sector gear 130 meshes with an agitator shaft pinion 138 which is loosely positioned upon the agitator shaft 48. The pinion is provided with a shifting collar 140 engaged by the stationary yoke 142 which may be raised or lowered by a rock shaft 144 and crank 146 acting upon a slide rod 148 to which the yoke 142 is securely attached. The rock shaft 144 is extended by suitable means such as a rod 149 through the skirt 18 to a control lever 150 at one end. At the other end, the rock shaft is provided with a crank 152 carrying a tension spring 154 extending to an integral bracket 156 formed in the cover plate 40. The spring is adapted to hold the rock shaft in either of its end positions shown at 152 and 152' in Figure 4. The connection between the crank 146 and the slide rod 148 comprises an arcuate slot 158 acting upon a cross pin 160 arranged in the slotted end 162 of the slide rod 148. The spring 154, by reason of the construction described, provided an over center toggle snap action in shifting the slide rod 148 and the pinion 138 upon the shaft 48.

The pinion 138 has a castellated hub extension 164 on its under side and the notches 166 thereof are adapted to engage the cross pin 168 in the shaft 48 when the pinion is in the position shown in Figure 5. The notches 166 are somewhat tapered, and by action of the compression spring 170 bearing against the yoke 142, the notches 166 are caused to tightly engage upon the pin 168 when the pinion is in the lowered position. Backlash is thus avoided which might otherwise result from the oscillating drive produced by the oscillating sector gear 130. It will appear that while the pinion 138 is actually shiftable to engage or disengage the pin 168, its axial movement is insufficient to at any time disengage from the sector gear 130.

The agitator drive shaft 48 is positioned in journal boss 172, bearing sleeve 182 in the housing 24 and the cover plate extension 44, respectively. End thrust is absorbed by a ball 176 located in the journal boss 172. The sleeve member 44 is composed of a tubular element 178 threaded into an integral portion 180 adjacent the elevated shoulder 52 of the cover plate 40, and is provided at its upper end with a bearing sleeve 182 and an adjacent shaft seal 184. A lock nut 186 bearing on a lead seal 187 renders the connection fluid-tight. Immediately above the clearance boss 174, the shaft is provided with a resilient annular slinger cup 188 adapted to throw any water traveling down the shaft away from the bearing end for drainage outside of the housing in the open space 189 provided in the cover plate 40 beneath the elevated shoulder 52. The plate 40 is accurately centered with respect to the housing 24 by the flange or shoulder 190 engaging the opening 34.

The drive to the extractor shaft 50 is accomplished through the helical gear train comprising the worm 94 and a driven gear 192, the latter being freely rotatably mounted upon the extractor drive shaft 50, the same being located between a collar 194 and its associated split ring 196 and a split ring 198. Slidably mounted upon the shaft 50 and keyed for rotation therewith, is a clutch and brake element 200 having a friction face 202. The element is resiliently urged downward by a compression spring 204 acting against an annular spring retainer 206 positioned on the shaft 50 by a split ring 208. The friction face 202 is caused to engage upon an end flange 210 integrally formed with the spiral gear 192, so that a friction drive is readily effected to the friction surface 202 and the shaft 50. In order to provide a brake for the shaft 50 and at the same time disengage the friction engagement of the flange 210 with the friction surface 202, there is provided a braking ring 212 having a friction face 214 which is adapted to be lifted into engagement with the friction surface 202, raising the sleeve 200 against the spring 204 to disengage the friction surface from the flange 210 and thereby brake the rotation of the shaft 50.

To actuate the clutch or brake at will, the annular brake ring 212 is supported on a fork 230 which is axially movable, the same being rigidly mounted upon a rod 232 slidable in suitable guide recesses 234 and 236 in the housing 24. The rod 232 is provided with rack teeth 238 engaging gear teeth 240 cut in the end of control shaft 242, so that by rocking the control shaft 242, the fork 230 is elevated or lowered to apply the brake or permit engagement of the clutch, respectively. A coupling 244 connects the control shaft 242 with a shaft 246 extending to the manually operated lever 248. In order to hold the clutch in engaged or disengaged position, a spring detent 250 is secured to the housing which cooperates with an arm 252 secured to the coupling 244. The spring detent 250 is provided with apertures 254 and 256 which cooperate with a blister 258 on the arm 252 to hold the arm 252 in either of two positions until manually and forcefully removed from such position. The detent also includes stop flanges 260 and 262 which limit the angular movement of the arm 252 and thereby limit the movement of the braking ring 212, and a yoke riding in an annular groove 263 in shaft 242 to prevent endwise movement.

The shaft 50 rotates in a journal boss 216 in the housing 24 and rests upon a thrust ball 218. The upper bearing for the shaft comprises a bearing sleeve 220 located within the upper end of the sleeve-like extension 46 of the cover plate 42. The latter is accurately located with respect to the aperture 38 by the flange 222 and is rigidly secured in place, as are the other cover plates previously referred to. The shaft is provided with a resilient slinger ring 221 to prevent water from entering the bearing.

The housing is adapted to be partially filled with oil through a filler plug 224 located in the side wall at a level substantially as indicated in Figure 4. A suitable drain plug 226 is provided so that the housing may be flushed if desired. It will thus be seen that while the worm 92 and helical pinion 94 may normally dip in oil, the eccentric, located beneath the worm wheel 108, actually runs in an oil bath. The level, however, is approximately at or below the shaft 82, so that leakage from the housing 24 is virtually impossible except for leakage at the packing 98, ar-

ranged around shaft 82, and leakage at this point is prevented, since the normal oil level within the housing is below the worm shaft and a suitable seal provided. A breather opening 225 relieves pressure, and extends substantially into the casing so that oil will be retained whether the casing be tipped in any direction as in shipping or servicing.

The shaft 82 may be squared or flattened at its end, and a suitable coupling such as 228 provided between the shaft and the motor shaft 330. The coupling may be similar to that disclosed in Patent No. 2,586,567, issued February 19, 1952. Secured to the housing 24 is a centrifuge pump 332 having a drive pulley 334 over which runs a belt 336 driven by a pulley 338 formed as a part of the coupling 228.

It will appear from the foregoing description that the housing, due to its integral construction comprising integral side walls as well as top except for the apertures to which the cover plates are attached, is extremely rigid. The housing is, in effect, a box beam. Its construction is such that it may readily be cast of light metals such as aluminum alloys or iron, as may be found desirable. Additionally, the journals for the various shafts are rigidly and accurately located with respect to the housing, and the construction is such that upon inserting the housing into the tub and skirt assembly of the washing machine, the bearing alignment of the moving parts is maintained despite tolerances in the tub and other parts secured to the housing or its cover plates. Thus, the bearings provided in the cover plates and housing may be closely fitted to avoid leakage of either lubricant outward or water inward. The journals for the moving parts and particularly the shafts 48 and 50, being rigidly located, positively maintain the moving parts in proper assembled relation with the result that wear is reduced to a minimum. Parts cannot be forced out of alignment in assembly. Force couples and twisting moments tending to twist the parts are likewise reduced to a minimum, since the eccentric is immediately adjacent the worm wheel and the connecting rod drives the sector gear through its bifurcated end and wrist pin. Each of the cover plates 40 and 42, together with their respective shafts, bearings and gears, and clutch mechanism, form sub-assemblies insertable into or removable from the transmission, and form the subject matter of divisional application Serial No. 283,681, filed April 16, 1952.

The operation of the transmission will be well understood by those skilled in the art, and from a consideration of the foregoing description. It will appear that the motor may run continuously and that the operator may at will couple the agitator or the extractor or both to their respective driving members as may be desired.

Although a single embodiment of the invention has been illustrated and described, it is to be understood that the invention is not limited thereto. As various changes in the construction and arrangement may be made without departing from the spirit of the invention, as will be apparent to those skilled in the art, reference will be had to the appended claims for a definition of the limits of the invention.

What is claimed is:

1. In a washing machine, a frame, a pair of tubs mounted side by side on said frame, each having a bottom with a central aperture therein, a rigid elongated transmission housing unit having rigid upstanding bearing sleeves forming an

integral part thereof extending upwardly through said apertures, a shoulder on each of said sleeves adapted to bear against each of said tub bottoms, means for securing said tub bottoms in bearing relation on said shoulders, and means for rigidly securing the transmission housing to said frame at its opposite ends and independent of said tubs.

2. In a washing machine, a frame, a pair of tubs mounted side by side on said frame, each having a bottom with a central aperture therein, a rigid elongated transmission housing a transverse box section, cover plates rigidly secured to opposite ends of the housing having broad bases engaging said housing and upstanding rigid bearing sleeves having tub bottom engaging shoulders, means for securing said shoulders rigidly against said tub bottoms with said sleeves extending through said apertures, and rigid means at either end of said housing for securing said housing to said frame independent of said tubs, whereby the frame and housing coact to strengthen one another.

3. In a washing machine, a frame, a pair of tubs mounted side by side on said frame, each having a bottom with a central aperture therein, a rigid elongated transmission housing of transverse box section and having top and bottom walls connected by a marginal low side wall, cover plates rigidly secured to opposite ends of the top wall of the housing, said cover plates having broad bases engaging said top wall and upstanding rigid integral bearing sleeves having tub bottom engaging shoulders and a short threaded portion immediately thereabove, threaded means on said threaded portion for clamping said tub bottoms between said shoulders and threaded means, and rigid means at the ends of said housing for securing said housing to said frame independent of said tubs.

4. In a washing machine, a frame, a pair of tubs mounted side by side on said frame, each having a bottom with a central aperture therein, a rigid elongated transmission housing of transverse box section and having top and bottom walls, cover plates rigidly secured to opposite ends of the housing each having a broad base rigidly engaging the top wall of said housing and an upstanding rigid integral bearing sleeve having tub bottom engaging shoulder, means for securing said shoulder rigidly against said respective tub bottoms with said sleeves extending through said apertures, a shaft extending through each of said sleeves, and a bearing for said shaft at the upper end of each of said sleeves, and rigid means at the ends of said housing for securing said housing to said frame independent of said tubs.

5. In a washing machine, a frame in the form of a continuous skirt, a pair of tubs mounted side by side on said frame, each having a bottom with a central aperture therein, a rigid elongated transmission housing unit having rigid upstanding bearing sleeves forming a part thereof rigidly secured thereto and extending upwardly through said apertures, drive shafts extending through said sleeves and journaled at the upper ends thereof, means on said sleeves for securing said tub bottoms thereto, and rigid means for securing the transmission housing to said frame at opposite ends independent of said tubs.

6. In a washing machine, a frame in the form of a skirt, a pair of tubs mounted side by side on said frame, each having a bottom with a central aperture therein, a rigid elongated transmission

housing unit having rigid upstanding bearing sleeves forming a part thereof rigidly secured thereto and extending upwardly through said apertures, drive shafts extending through said sleeves and journaled at the upper ends thereof, a shoulder on each of said sleeves adapted to bear against each of said tub bottoms, and means for securing said tub bottoms in bearing relation on said shoulders, and rigid means for securing the transmission housing to said frame at opposite ends independent of said tubs.

7. In a washing machine, a frame, a pair of tubs mounted side by side on said frame, each having a bottom with a central aperture therein, a rigid elongated transmission housing unit having two rigid upstanding bearing sleeves forming a rigid part thereof extending upwardly through said apertures, drive shafts in said sleeves journaled at the upper ends thereof, means on said sleeves for securing said tub bottoms thereto, and rigid means for securing the transmission housing to said frame at opposite ends independent of said tubs.

8. In a washing machine, a frame, a pair of tubs mounted side by side on said frame, each having a bottom with a central aperture therein, a rigid elongated transmission housing unit having rigid upstanding bearing sleeves forming a rigid part thereof extending upwardly through said apertures, a shoulder on each of said sleeves adapted to bear against each of said tub bottoms, and means for securing said tub bottom in bearing relation on said shoulders, drive shafts extending through said sleeves and journaled in the upper ends thereof and the bottom of said housing unit, a horizontal diagonal shaft extending into said housing, a motor secured to the outside of said housing in line with said shaft and coupled thereto, a pair of worm gears on said shaft, a worm wheel and eccentric journaled in the top and bottom walls of said housing unit, said wheel meshing with one of said worms and being located above said eccentric, a connecting rod driven by said eccentric connected to a sector gear and crank journaled in the top and bottom walls of the unit, said rod being bifurcated at said gear, and a pinion on one of said drive shafts meshing with said sector gears, and means for clutching said pinion at will with the last named drive shaft and means for rigidly connecting said housing to said frame at opposite ends and independent of said tubs.

9. In a washing machine of the two-tub agitator and extractor type, a transmission having a housing formed from a single one-piece elongated hollow flat rigid box section casting having attachment lugs at each end thereof and adapted to form a frame member, said casting having bottom and top walls, and peripheral side walls, a diagonal horizontal shaft, projecting through the side wall centrally of the length thereof and extending to one end of the housing, said top wall having three large openings, one at either end and one centrally located, cover plates for each of said openings, the end cover plates having upstanding bearing sleeves having tub bottom engaging shoulders below the upper end thereof, and the center cover plate being concave and extending partially into said housing, said cover plates having journals therein in alignment with integral internal recess journals in the bottom wall of said housing, agitator and extractor vertical drive shafts projecting from said sleeves and journaled therein and in the respective said housing journals, and gearing carried by said vertical shafts,

diagonal shaft, and housing and cover plate journals for driving said shafts from said diagonal shaft, said housing being impervious below the projecting diagonal shaft.

10. In a washing machine of the two-tub agitator and extractor type, a transmission having a housing formed from a single one-piece elongated hollow flat rigid box section casting having lugs at each end thereof and adapted to form a frame member, said casting having bottom and top walls, and peripheral side walls, a diagonal horizontal shaft, projecting through a thrust bearing in the side wall centrally thereof and extending to one end of the housing and having spaced drive worms thereon, shaft end thrust means mounted in the housing side wall is alignment with the shaft end, said top wall having three openings, one at either end and one centrally located, cover plates for each of said openings, the end cover plates having upstanding bearing sleeves, and the center cover plate being concave and extending partially into said housing, said cover plates having journals therein in alignment with integral internal recess journals in the bottom wall of said housing, agitator and extractor vertical drive shafts projecting from said sleeves and journaled therein and in the respective said housing journals, and gearing including worm driven wheels in engagement with the worms of said diagonal shaft carried by said vertical shafts, 30 diagonal shaft, and housing and cover plate journals for driving said shafts from said diagonal shaft.

11. In a washing machine of the two-tub agitator and extractor type, a transmission having a housing formed from a single one-piece elongated hollow flat rigid box section casting having lugs at each end thereof and adapted to form a frame member, said casting having bottom and top walls, and peripheral side walls, a diagonal horizontal shaft having a worm thereon, projecting through the side wall centrally thereof and extending to one end of the housing, and three large openings in the top wall, one at either end and one centrally located, cover plates for each of said openings, the end cover plates having upstanding bearing sleeves, and the center cover plate being concave and extending partially into said housing, said cover plates having journals therein in alignment with integral internal recess journals in the bottom wall of said housing, agitator and extractor vertical drive shafts projecting from said sleeves and journaled therein and in the respective said housing journals, and gearing carried by said vertical shafts, diagonal shaft, and housing and cover plate journals for driving said shafts from said diagonal shaft, said gearing including a worm wheel meshing with said worm, and an eccentric therebelow journaled in said center cover and housing.

12. In a washing machine of the two-tub agitator and extractor type, a transmission having a housing formed from a single one-piece elongated hollow flat rigid box section casting having lugs at each end thereof and adapted to form a frame member, said casting having bottom and top walls, and peripheral side walls, a diagonal horizontal shaft having a worm thereon, projecting through the side wall centrally thereof and extending to one end of the housing, and three large openings in the top wall, one at either end and one centrally located, cover plates for each of said

openings, the end cover plates having upstanding bearing sleeves, and the center cover plate being concave and extending partially into said housing, said cover plates having journals therein in alignment with integral internal recess journals in the bottom wall of said housing, agitator and extractor vertical drive shafts projecting from said sleeves and journaled therein and in the respective said housing journals, and gearing carried by said vertical shafts, diagonal shaft, and housing and cover plate journals for driving said shafts from said diagonal shaft, said gearing including a worm wheel meshing with said worm and an eccentric therebelow journaled in said center cover and housing, a crank journaled in the end plate and housing having an eccentric engaging connecting rod in alignment with said crank and eccentric.

13. In a washing machine, a supporting frame comprising a sheet metal skirt for supporting two tubs side by side, a transmission unit comprising a relatively flat rigid elongated casing having top and bottom walls arranged longitudinally within the skirt, and having rigid connections to the skirt at spaced triangularly disposed end points, whereby said casing and skirt cooperate to provide a rigid structure, tub seats formed by the upper edge of said skirt, tubs positioned side by side on each of said seats, each of said tubs having a tub bottom having a central aperture, upstanding sleeves formed integrally with parts of the top wall of said casing and projecting through each of said bottom apertures, means to seal said apertures about said sleeves, and an internal shaft for driving a laundry device within each of said tubs extending downwardly through each of said sleeves and into said casing and journaled in the respective sleeves and the bottom wall of said casing and supporting legs secured to said skirt at each of said triangularly disposed end points, said frame and rigid casing serving to rigidify said supporting legs.

14. In a washing machine, a tub supporting frame comprising an elongated sheet metal skirt having rounded ends, a pair of circular tubs mounted side by side on said frame, said frame having circular seats for receiving said tubs adjacent the bottoms thereof, each of said tubs having a bottom and a central aperture therein, a transmission unit having a rectangular sectioned elongated casing positioned within said skirt and rigidly secured to said skirt at opposite ends independent of said tubs, said casing having as a part thereof broad base cover plates with integral upwardly extending sleeves, aligned with and projecting through said tub bottom apertures, and means for securing said tub bottoms to said sleeves.
